HENRY THOMAS, OF RIDLEY PARK, CLARENCE H. THAYER, OF MEDIA, AND FREDERICK A. THORNGATE, OF CHESTER, PENNSYLVANIA, ASSIGNEES TO SUN OIL COMPANY, OF PHILADELPHIA, PENNSYLVANIA, A CORPORATION OF NEW JERSEY

PROCESS FOR COOLING AND SAFEGUARDING OIL CRACKING APPARATUS

Application filed March 20, 1930. Serial No. 437,352.

Our invention relates to the art of cracking hydrocarbon oils by subjecting oil flowing through tubes to a cracking temperature for a sufficient length of time to effect a part or 5 all of the desired cracking.

In the operation of this type of cracking apparatus it is necessary to periodically shut it down for the purpose of removing from the interior of the heating coils a carbonaceous deposit which accumulates during the 10 processing of oils. Before starting the actual cleaning operation it is necessary to cool the furnace containing the heating coils and remove the oil and oil vapors from the coils. 15 This is frequently accomplished by forcing through the tubes, after the furnace fires have been turned out, relatively cold oil, which gradually absorbs the heat contained in the furnace brickwork and tubes, after which 20 steam under pressure may be turned into the coils to remove the oil vapors. Such procedure requires a considerable amount of time and it is desirable, from a commercial standpoint, to reduce this non-operating time to 25 the practicable minimum.

One of the main objects of the invention is to more quickly cool the heating coils when it is desired to shut down the apparatus. Another object of the invention is to reduce 30 the expense of the cooling operation.

During the cracking operation, any serious oil leak or break may result in a serious fire. Still another object of the invention is to 35 provide safeguards against serious results in the event of leakage or breakage.

Our invention involves a means and process of cooling which eliminate the cost of pumping oil through the coils for cooling effect and eliminate, also, the introduction 40 of boiler-produced steam into the coils for the purpose of removing oil and oil vapors. The equipment for cooling the heating coils is, to a substantial extent, the same equipment that is available for use, in case of leak- 45 age or breakage, to prevent serious consequences.

The invention is adaptable to various cracking plants and processes and may be embodied in many different forms. To illustrate 50 the invention, we have shown, in the

accompanying drawing, a diagram of a typical cracking plant provided with equipment adapted to effect the objects hereinbefore specified.

The heating coil 2 is placed in a furnace 1. 55 The heating coil may consist of a plurality of tubes or sets of tubes connected in series or in parallel. Element 3 is a heat exchanger utilized to cool the cracked oil to the desired temperature for further processing and 60 which returns the excess heat so removed to the charging stock entering heating coil 2 through pipe line 13. Tank 4 contains the oil to be processed. Pump 5 removes the oil from tank 4 through pipe line 6 and forces 65 it through heat exchangers 7 and 8. These heat exchangers 7 and 8 transfer heat from some of the products from fractionating tower 9 to the charging oil. From these heat exchangers the oil flows through pipe 70 line 10, in which is interposed a pump 11 which provides the high pressure required to force the oil through heat exchanger 3, heating coil 2, line 13 and throttle valve 12. After being heated and cracked in heating 75 coil 2 the oil passes out through pipe line 13, throttle valve 12, heat exchanger 3, and thence into fractionating tower 9 where the cracked oil is separated into the desired products. 80

Gasoline vapor or distillate, together with the so-called fixed or incondensable gases, passes from the top of fractionating tower 9 through line 14 into condenser 15 and thence into gas separator 16. The incondensable gases are disposed of through line 17 and gasoline or distillate through line 18 into receiver 19. A portion of the gasoline is pumped from gas separator 16 by means of line 20 and pump 21 into the upper part 85 of fractionating tower 9 in order to be re-vaporized and thus absorb the required amount of heat to effect refluxing in fractionating tower 9.

An intermediate product, which normally 90 will be gas oil, passes from the central section of tower 9 through line 22 and heat exchanger 7 and thence to receiver 23 through line 24.

A heavier product, which will ordinarily 100

be used as fuel oil, passes from the bottom of tower 9 through line 25, heat exchanger 8, and cooler 26 to receiver 27.

The above description discloses the flow 5 of oil in the normal cracking process, during which the carbonaceous deposit accumulates in heating coil 2, pipe line 13, and perhaps heat exchanger 3. This deposit tends to decrease the heat transfer between the furnace 10 gases or other heating medium and the oil. It increases the amount of pressure required to force the oil through heating coil 2 and by its insulating action tends to cause over-heating of the metal tubes comprising the 15 heating coils. Consequently it becomes necessary to shut down the equipment and clean it.

Because of the inflammable nature of the material being processed, it is common practice to provide, for use in emergencies, a 20 means for quickly disposing of the oil in the system. In the apparatus being described, two such provisions are made. The first provision consists of pipe line 28, and a hand or power operated valve 29, which may be 25 opened to quickly discharge the oil from heating coil 2 into a suitable receiver or stack 31, which is located at a safe distance from the cracking apparatus; also an automatic relief valve 30 which opens in the case of an 30 excess pressure in the system and which also discharges to the same receiver or stack. Water is sprayed into the top of the stack by means of line 32 for the purpose of cooling 35 the oil vapor as it rises through the stack. A sewer 33 is furnished to dispose of the condensed oil and water. The second provision consists of a so-called circulating system 40 consisting of a water-cooled coil 34 through which the oil leaving heat exchanger 3 may be discharged, by means of line 35 and valve 36, into tank 4 or tank 23. This circulating coil 34 may be used to cool the oil passing from heating coil 2 and heat exchanger 3 at 45 any time it is not desired to put it into tower 9.

A water supply line 37 is connected to the suction of charging pump 11 and is so arranged that by manipulation of valves 38 50 and 39 the charging oil may be shut off and water introduced into the pump.

The following procedure is observed in shutting down the processing equipment:

The fuel to the burners in the furnace is 55 shut off. Valve 38 is opened which admits water to the suction of charging pump 11. Check valves 40 and 41 prevent water from backing into oil line 10 or oil from entering water line 37 depending upon whether the 60 oil pressure or water pressure is the higher. Valve 39 on oil line 10 is shut off. Pump 5 is then stopped. The amount of water passing through pump 11 is regulated as desired either by changing the speed of the pump or 65 by throttling the discharge of the pump by

means of valve 42. The water rate is regulated as necessary so as to maintain an established pressure at the discharge side of pump 11. This pressure generated by pump 11 and the pressure of the steam into which the water is converted when it reaches the hot sections of the apparatus drive the oil and oil vapors out of heating coil 2 through line 13. The amount of time required to do this is of course largely dependent upon the pressure maintained on the system and the volume of oil to be displaced. The plant operators learn by experience the approximate time required and before water or steam reaches the outlet of heating coil 2 a small bleeder valve 43 in line 13 is opened. As soon as steam or water appears at bleeder valve 43 emergency valve 29 is opened and valve 44 on line 13 at the inlet to tower 9 is closed, thus permitting the water vapor to discharge into the bottom of stack 31 through line 28. Pumping of water into heating coil 2 is continued until the temperature has dropped enough to permit the tube 75 cleaning crew to begin work.

It will be realized that, due to the specific heat and latent heat of evaporation of water being much higher than that of oil, the apparatus is cooled down to the desired temperature within a small fraction of the time 85 that would be required by circulating cold oil through the tubes. Furthermore, the removal of oil and oil vapors from the heating coil has been accomplished during this cooling 90 period.

One of the features of the invention not yet described consists of means for quickly dissipating the pressure existing in heating coil 2 after water has been forced into it for the desired amount of time. The heating coil in such an apparatus may consist of several thousand feet of tubing connected in series. A considerable amount of time would be required to relieve the water vapor pressure 105 from one or both ends of the coil, especially 110 since the water laying in the tubes continues to evaporate after the pumping is discontinued. Furthermore, it is not considered safe to remove plugs from the return bends 115 connecting the tubes until the pressure in the tubes is practically atmospheric, as otherwise workmen engaged in the work might be scalded.

Connections into the return bends with 120 valves 45 have been provided which are opened as soon as pumping of the water into heating coil 2 is discontinued. The water vapor under pressure is thus permitted to escape at a plurality of openings. If disagreeable to discharge the vapor into the atmosphere, pipe connections 46 to available 125 sewers may be provided. Ordinarily these are disconnected during cracking operation of the apparatus and blank flanges are bolted to the outlet of the valves 45. This is done to 130

preclude the possibility of oil leaking through the valves 45 and into the sewer and escaping observation by the plant operators.

Having now full described our invention, 5 what we claim and desire to protect by Letters Patent is:

1. The process of cooling the heating coil of an oil cracking apparatus in which hydrocarbon oil under pressure flows continuously 10 through a pipe coil which is subjected to heat sufficient to raise the oil to a cracking temperature, and in which cracked hydrocarbon flows towards a fractionating equipment, which comprises discontinuing the supply of 15 heat to the coil, flowing water under pressure through heat interchanging apparatus, wherein the water is heated by fluid from the coil, and thence through the coil, thereby effecting conversion of water into steam and 20 driving oil ahead of the steam and water out of and beyond the coil and beyond the heat exchanging apparatus, and at about the time that steam begins to outflow from the pipe coil by-passing the steam, then continuing 25 the flow of water through the pipe coil and by-passing the same until the pipe coil has cooled sufficiently to permit manual operation thereon, and then venting the pipe coil intermediate its ends to quickly dissipate the 30 pressure therein.

2. The process of cooling the heating coil of an oil cracking apparatus in which hydrocarbon oil under pressure flows continuously through a pipe coil which is subjected to heat sufficient to raise the oil to a cracking temperature, and in which cracked hydrocarbon flows towards a fractionating equipment, which comprises discontinuing the supply of 70 heat to the coil, flowing water under pressure through heat interchanging apparatus, wherein the water is heated by fluid from the coil, and thence through the coil, thereby effecting conversion of water into steam and 75 driving oil ahead of the steam and water out of and beyond the coil and beyond the heat exchanging apparatus, and at about the time that steam begins to outflow from the pipe coil by-passing the steam, flowing the bypassed steam together with oil vapor mixed therewith toward a locus of cooling, flowing 80 water to said locus to effect the cooling of the oil vapor by intimate contact therewith, and continuing the flow of water through the pipe coil and by-passing the same until the pipe coil has cooled sufficiently to permit 85 manual operation thereon.
